(57) CLAIM

The ornamental design for a golf club head, as shown and described.

DESCRIPTION

FIG. 1 is a top perspective view of a golf club head; FIG. 2 is a bottom perspective view of the golf club head of FIG. 1;

FIG. 3 is a front view of the golf club head of FIG. 1;

FIG. 4 is a rear view of the golf club head of FIG. 1;

FIG. 5 is a top view of the golf club head of FIG. 1;

FIG. 6 is a bottom view of the golf club head of FIG. 1;

FIG. 7 is a left view of the golf club head of FIG. 1; and,

FIG. 8 is a right view of the golf club head of FIG. 1.

The broken line showing is included for the purpose of illustrating and forms no part of the claimed design.
